UNITED STATES PATENT OFFICE.

JOB HUTCHINSON, OF ASTORIA, NEW YORK.

INTERNAL-COMBUSTION ENGINE.

1,246,272.

Specification of Letters Patent. Patented Nov. 13, 1917.

Application filed March 25, 1916. Serial No. 86,772.

To all whom it may concern:

Be it known that I, Job HUTCHINSON, a citizen of the United States, residing at Astoria, in the county of Queens and State of New York, have invented new and useful Improvements in Internal-Combustion Engines, of which the following is a specification.

This invention relates to internal combustion engines and has to do with the arrangement and relation of the piston and main drive shaft together with the connecting drive means between these parts.

One object of the invention is to provide an internal combustion engine so designed that the time required for overhauling and the cost of maintenance will be considerably reduced.

Another object of the invention is to provide a central plant having a multiple number of detachable power units, which units may be removed from the central plant without delaying the operation of the machine and without impairing the efficiency of the other power units.

Another object of the invention is to eliminate friction and make it possible to advantageously use roller bearing or ball bearings to support the main drive shaft.

Another object of the invention is to provide an internal combustion engine which will operate without the use of a multiplicity of parts such as cam shafts and timing gears and which in principle may be adapted to use in either stationary or rotary engines.

It has been found of advantage to increase the number of power units in engines rather than to increase the size of the individual units in order to increase the horse power of the machine. By my invention the increase in units may be made practically without end and this may be accomplished without interfering with the relation of the first units to the driven parts and without causing severe shock to fall on the main shaft bearings as would be the case where the size of the power units is increased.

Other features of the invention and details of the construction involving these features will be pointed out, described and claimed in the following specification and claims and shown in the accompanying drawings in which:

Figure 1 represents a sectional view of

one type of internal combustion engines illustrating the use of a spur type of gear and the relation between the power unit at the top which is detachable in its entirety from the central gear on the main drive shaft. This view indicates the space between the two members of the main gear provided for the swinging movement of the connecting rod of the upper power unit between these parts.

Fig. 2 is a plan view with the removable cylinder head detached, illustrating the valve heads with the openings for the passage of the cooling water.

Fig. 3 represents in section four power units placed in the upper half of an engine and illustrating as in Fig. 1 how the individual units may be detached without interfering with the operation of the other members, by simply removing the cylinder head.

Fig. 4 is an enlarged view of the individual power units, showing the driving gear mounted in bearings provided by the extensions of the power unit.

Fig. 5 represents in section a side view of the structure shown in Fig. 4.

Fig. 6 is an enlarged view of the valve cage showing the valve and spring in place and a ball bearing mounted in the lower end of the valve rod for engagement with the cam surface of the large cam mounted on the central drive shaft.

Fig. 7 represents diagrammatically a central gear case having a main shaft provided with a multiple number of cylinders to indicate the position of the power units when the invention is applied to an eight cylinder V-type motor.

Like numerals refer to like parts throughout the various figures.

Referring in detail to the structures illustrated 1 represents the main drive shaft of the engine which is provided with suitable bearings 2 for supporting this shaft. 3 represents a main drive gear connected to and rigidly keyed to the shaft 1. 4 represents a central casing or housing which incloses the drive shaft 1, its bearings 2, the large gear 3 and suitable cams 5 which are provided to actuate the valves of the separable units. Referring particularly to the structure shown in Fig. 1 the central gear 3 is shown as formed of the herring bone type but unlike the usual forms the two sides of the gear are separated although rigid in respect to each other. The unitary power unit

is inclosed within the casting 6 which is provided with openings for the piston 7, cylinder walls 8 and valves 9. Extending down as continuation from the cylinder walls are 5 the projections 10 which form and provide supporting bearings for the power unit drive gears 11 which are adapted to mesh with and drive the central gear 3. Eccentrically mounted on the gears 11 and between the 10 two is a shaft 12 mounted on which is the connecting rod bearing on the end of the connecting rod 13. The casing 4 is fastened to the casting 6 by bolts 14. Suitable intake and exhaust ports are provided for the 15 valves 9 and on the lower end of the valve rod is mounted a ball bearing for engagement with the cam 5. The cylinder head 15 may be removed bodily from the top of the casting 6 by removing the bolts 17. The 20 cylinder head is provided with the usual ignition plug 16. The casting 6 provides a ledge 6^a around openings through which the power unit projects and the valve rods extend. As shown in Fig. 2 the power unit 25 and the valve cages may be bodily removed from the casting 6. In this form the cams 5 revolve in a bath of oil in the main chamber 4 and throw this oil over the central gear 3 which carries it up to and in engagement 30 with the smaller gear 11.

In the structure illustrated in Fig. 3 four power units have been mounted for engagement with the central gear 3. This view is at right angles with the structure shown in 35 Fig. 1 and practically a section taken centrally of Fig. 1. The main casting 6 is illustrated as being approximately circular and having a continuous annular chamber 18 for the passage of cooling water. The in- 40 take or exhaust ports are illustrated in dotted lines opposite the piston 7.

Referring to Figs. 4 and 5 in detail, it will be observed that these are enlarged views of the power units showing the 45 mounting for the bearing of the smaller gears in the projections of the unit cylinder walls. Fig. 6 shows an enlarged view of the valve member and cage provided with the spring and the proper bearing for the valve 50 9. The ball in the base of the rod may be easily seen in this view.

Fig. 7, as mentioned before represents diagrammatically the arrangement of a multiple cylinder V type engine such as might be 55 used in automobile structures. The main drive shaft 1 and the main casting 6 have mounted above them the removable cylinder heads 15, covering the power units.

From the foregoing description it will be 60 obvious that this invention provides a novel type of internal combustion engine structure in which the separate cylinders may be detached without interfering with the working parts of the other cylinders and without the

trouble incident to the removal of the working parts in the engines of present day construction. The power units may be removed without changing the timing of the engine and without interfering with the cams. When necessary to repair or adjust the type 65 of engine herein described, it is only necessary to have a spare unit and to insert this unit into the place of the one to be repaired. Obviously this means great saving in that machinery may be kept in practically constant use and the time incident to the repair 70 may be made without removing the engine from its daily service.

By the present invention the use of roller or ball bearings may be permitted because 75 vibration is so reduced and distributed that no shock falls directly on the main shaft bearings. With the gearing arranged two to one the piston speed is increased from two to four cycles per revolution which gives one 80 explosion to each cylinder for every revolution of the main shaft and thus making a six cylinder engine of this type, bore for bore, equal to a twelve cylinder engine of the present crank shaft construction. Moreover cam shafts and timing gears are dispensed with and the main bearing friction 85 is largely eliminated.

Another feature of this type of engine is the reduced weight per horse power and the 90 small space occupied.

In the type of engine illustrated in the drawings, it will be observed that the double spur gears with the teeth of the double helical type will give the effect of the herring bone gear. In this engine, however, the sides of the herring bone gear have been grooved out in their center to allow the end of the connecting rod to operate between 95 the smaller gears.

It will be obvious that it may be possible to provide a driven shaft in cases where it has been illustrated as stationary and to cause the cylinders to rotate where they have been shown as stationary and vice versa as 100 may be desired. Such changes as are necessary in the supporting members to accommodate such changes in the size, shape or the relation of parts may be made without departing from the scope of the invention. 105

What I claim is:

1. In an internal combustion engine of the character described, a main casing, a driven shaft mounted in said casing, bearings for said shaft in opposite sides of said 110 casing, a main gear rigidly secured to said shaft, and a unit power plant detachably secured to said main casing, said unit power plant including a piston, crank shaft and crank shaft bearings and gear arranged to 115 mesh with said main gear, said unitary power plant being removable as a unit from said casing.

2. In an internal combustion engine of the character described, a main casing, a driven shaft mounted in said casing, bearings for said shaft in opposite sides of said casing, 5 a main gear rigidly secured to said shaft, said casing being provided with an opening for the insertion of a drive member for said main gear, and a unit power plant detachably secured to said main casing and constituting a drive member for said main gear, said unit power plant including a piston, cylinder walls, extensions on opposite sides of said cylinder walls, crank shaft bearings and a gear arranged to mesh with said main 10 gear and mounted between said extensions, said extensions fitting into said opening and said unitary power plant being removable as a unit from said casing. 15 3. In an internal combustion engine of the character described, a support member, a unit power plant mounted on said support member having an engine cylinder, a piston, extensions projecting in a line with the walls of said cylinder, bearings carried by 20 said extensions, a crank shaft mounted in said bearings, a gear mounted in conjunction with said crank shaft, and a connecting rod between said piston and said crank shaft, said unitary power plant being removable as a unit from said support member. 25 4. In an internal combustion engine of the character described, a supporting casing, a driven member within said casing, and a removable power unit mounted on said supporting casing comprising a cylinder, extensions in alignment with said cylinder, a crank member carried by said extensions, a piston within said cylinder, a connecting rod 30 between said crank member and said piston, and connecting drive means between said crank member and said driven member, said unitary power plant being removable as a unit from said supporting casing and 35 driven member. 40 5. In an internal combustion engine of the character described, a support member, a unit power plant mounted on said support member and having an engine cylinder, a piston, extensions of the walls of said cylinder formed in one piece with said cylinder and extending in a line therewith, bearings carried by said extensions, a crank shaft mounted in said bearings, a gear mounted on 50 said crank shaft, and a connecting rod between said piston and said crank shaft, said unitary power plant being removable as a unit from said support member. 55 6. In an internal combustion engine of the character described, a main casing, a driven shaft mounted on said casing, a main gear mounted on said shaft and having an annular groove centrally located around the periphery of the same, and a unit power plant 60 detachably secured to said main casing, said unit power plant including a cylinder, a piston, extensions projecting from opposite sides of said cylinder and axially therewith, crank shaft and crank shaft bearings in said extensions and a secondary gear between 65 said extensions arranged to mesh with said main gear on said driven shaft, said annular groove providing space for the movement of said connecting rod between the divisions of 70 said gear. 75 7. In an internal combustion engine of the character described, a main casing, a driven shaft mounted on said casing, a main gear mounted on said shaft and having an annular groove centrally located around the periphery of the same, and a unit power plant detachably secured to said main casing, said unit power plant including a cylinder, a piston, extensions on opposite sides of said cylinder projecting axially therewith, a crank shaft and crank shaft bearings in said extensions, and a secondary gear between 80 said extensions arranged to mesh with said main gear on said driven shaft, said annular groove providing space for the movement of a connecting rod between the divisions of 85 said gear, said unitary power plant being removable as a unit from said main casing. 90 8. In an internal combustion engine of the character described, a main casing, a driven shaft mounted in said main casing, a main gear rigidly secured to said shaft, a cam rigidly secured to said shaft, and a unit power plant detachably secured to said main casing, said unit power plant including a cylinder wall, a piston, a crank shaft and crank shaft bearings, a gear adapted to engage with said main gear, and valves and 95 valve rods adapted to engage with said cam and to be operated thereby. 100 9. In an internal combustion engine of the character described, a substantially circular cast metal ring having a central bore for the passage of cooling water, drum heads fastened to either side of said ring and providing supporting bearings for a shaft, and a unitary power plant secured to said cast metal ring and said drum heads and having ports therein for the passage of cooling water, the central bore of said cast metal ring 110 communicating with the ports in said unitary power plant. 115 10. In an internal combustion engine of the character described, a substantially circular cast metal ring having a central bore for the passage of cooling water, drum heads fastened to either side of said ring, a shaft passing through said drum heads, a main gear on said shaft, and a detachable unitary power plant secured to said cast metal ring and said drum heads and having ports 120 therein for the passage of cooling water, 125

the central bore of said cast metal ring communicating with the ports of said unitary power plant, said unitary power plant including a piston, crank shaft and crank shaft bearings and a secondary gear adapted to engage with said main gear.

5 In testimony whereof I have hereunto set

my hand in presence of two subscribing witnesses.
